UNITED STATES PATENT OFFICE

117,475

DESIGN FOR A GLOBE FOR LIGHTING FIXTURES

Gustave A. Gustafson, Meriden, Conn., assignor to General Electric Company, a corporation of New York

Application January 11, 1939, Serial No. 82,292

Term of patent 14 years

To all whom it may concern:

Be it known that I, Gustave A. Gustafson, a citizen of the United States, residing at Meriden, in the county of New Haven and State of Connecticut, have invented a new, original, and ornamental Design for a Globe for Lighting Fixtures, of which the following is a specification, reference being had to the accompanying drawing, forming a part thereof.

In said drawing:

Figure 1 is a side view of a globe for lighting fixtures embodying my new design.

Figure 2 is a bottom view of the globe.

The design comprises a globe of the specific configuration shown having a bead at the base thereof and provided with groups of ornamental fluting, each group consisting of flutes relatively closely spaced at the base of the globe and extending vertically upward from the base in divergent fashion as shown.

I claim:

The ornamental design for a globe for lighting fixtures, substantially as shown and described,

GUSTAVE A. GUSTAFSON.
